UNITED STATES PATENT OFFICE.

ELLA PALMER, OF NEW YORK, N. Y.

PACKAGE-CARRIER.

1,137,523.

Specification of Letters Patent. Patented Apr. 27, 1915.

Application filed October 24, 1914. Serial No. 868,370.

To all whom it may concern:

Be it known that I, ELLA PALMER, a citizen of the United States, and residing at New York, in the county of New York and 5 State of New York, have invented certain new and useful Improvements in Package-Carriers, of which the following is a specification, such as will enable those skilled in the art to which it appertains to make and 10 use the same.

This invention relates to devices for carrying packages, small or large, and of various kinds and classes, and the object thereof is to provide an improved device of 15 this class which is simple in construction and operation, comparatively inexpensive, and which may be quickly and easily applied to a package of any kind secured or tied by a cord or other flexible device, and which may 20 also be conveniently carried in a pocket or in a small bag, and which may be used as an advertising device, if desired.

The invention is fully disclosed in the following specification, of which the accompanying drawing forms a part, in which the 25 separate parts of my improvement are designated by suitable reference characters in each of the views, and in which:—

Figure 1 is a perspective view showing the 30 method of applying and using my improved package carrier device; Fig. 2 a sectional view of the device detached; and, Fig. 3 a partial section on the line 3—3 of Fig. 2.

In the drawing forming part of this specification, I have shown at *a* an ordinary package secured or tied by a cord *b* which is passed around said package centrally and longitudinally, and centrally and transversely in the usual or any desired manner.

40 My improved package carrier device comprises an oblong handle portion *c* which is trough-shaped, semi-circular or loop-shaped in cross section, as clearly indicated in Figs. 1 and 2 and as shown in Fig. 3, and the 45 handle portion is provided in the bottom thereof and at equal distance from the ends thereof with holes or apertures *c*² and *c*³, and in the top side portions thereof and adjacent to each end thereof with notches or 50 recesses *c*⁴. I also provide a cord or similar flexible device *d* which is folded centrally to form a loop *d*² and two end portions *d*³ and *d*⁴, the end portion *d*³ being longer than the end portion *d*⁴.

In connecting the cord *d* with the handle 55 *c*, the loop *d*² is passed upwardly through the hole or aperture *c*² and longitudinally through said handle and down through the hole or aperture *c*³ and tied into a knot *d*⁵ after which the end portions *d*³ and *d*⁴ are 60 tied together to form a knot *d*⁶ and a loop *d*⁷ similar to the loop *d*².

In the use of this device the loop members or parts *d*² and *d*⁷ are passed one or more times around the parts *b*² of the package 65 securing cord *b* and the end parts of said loop portions or members are wrapped around the other parts *d*⁸ thereof, as clearly shown in Fig. 1, and said end parts are slipped on over the ends of the handle *c* and rest in 70 the notches or recesses *c*⁴ as clearly shown at *d*⁹. This operation of connecting the handle with the package to be carried may be quickly and easily performed without the 75 tying of knots, and said handle may be as quickly and easily detached from the package by slipping the loop members off of the end portions of said handle.

The handle *c* may be made of any desired material and may be made of any preferred 80 shape in cross section, and changes in and modifications of the construction described may be made, within the scope of the appended claims, without departing from the spirit of my invention or sacrificing its ad- 85 vantages.

Having fully described my invention, what I claim as new and desire to secure by Letters Patent, is:—

1. A package securing and carrying device, comprising an oblong hollow handle the bottom of which is provided adjacent to its opposite ends with holes or apertures, and the top side portion of which is provided adjacent to its opposite ends with transverse 90 recesses, and a cord passed longitudinally through the handle between said holes or apertures and through said holes or apertures and the end portions of which are provided with loops of predetermined length 95 which depend from said handle.

2. A package securing and carrying device, comprising an oblong trough-shaped handle, the bottom of which is provided adjacent to its opposite ends with holes or 105 apertures and the top side edge portion of which is provided adjacent to its ends with transverse recesses, and a cord passed

through said handle between said holes or apertures and the ends of which are passed outwardly through said holes or apertures and provided with loops of predetermined length.

In testimony that I claim the foregoing as my invention I have signed my name in

presence of the subscribing witnesses this 22nd day of October 1914.

ELLA PALMER.
